UNITED STATES PATENT OFFICE.

CHARLES WALLACE, OF DENVER, COLORADO.

ROCK-CRUSHER.

SPECIFICATION forming part of Letters Patent No. 773,107, dated October 25, 1904.

Application filed November 22, 1902. Serial No. 132,477. (No model.)

To all whom it may concern:

Be it known that I, CHARLES WALLACE, a citizen of the United States of America, residing at Denver, in the county of Arapahoe and State of Colorado, have invented certain new and useful Improvements in Rock-Crushers; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in rock-crushers; and it consists of the features, arrangements, and combinations hereinafter described and claimed, all of which will be fully understood by reference to the accompanying drawings, in which is illustrated an embodiment thereof.

In the drawings, Figure 1 is a vertical section of the machine taken on the line 1 1, Fig. 3. Fig. 2 is a horizontal section taken on the 20 line 2 2, Fig. 1. Fig. 3 is a section taken on the line 3 3, Fig. 1.

The same reference characters indicate the same parts in all the views.

Let the numeral 5 designate each of two 30 bottom beams located at the ends of the machine and extending transversely of the framework mounted thereon. This framework is composed of two side beams 6, secured to the bottom beams by bolts 7. The beams 6 are 35 suitably separated to receive the lower portion of a vertically-moving lever-bar 8, to which is attached a crushing-jaw 9, which is held in place above by a wedge-shaped clamping-block 10, the latter being secured to the 40 lever-bar by bolts 12. The lower extremity of the jaw 9 is provided with lugs 9^d, which pass between the metal plates of the lever-bar 8. The latter is also provided with projections 8^d, having beveled upper faces to engage counterpart notches formed in the jaw 9 adjacent the lugs 9^d. This construction 45 operates with the clamping-block 10 to hold the jaw securely in place. A bolt 9^b passes through the lugs 9^d of the jaw and further secures the said jaw to the lever-bar. This bar

is hung and swings upon an eccentric-shaft 12^a, journaled in suitable bearings 14, mounted on the upper extremities of side frame-bars 15, there being two of these bars on each side of the lever-bar, each pair of bars 15 being 55 connected at the top by bolts 16 and separated below where they diverge in the form of a letter A, their lower extremities having tenons which enter mortises formed in the horizontal side frame-beams 6, as shown at 15^a. To the 60 lower part of each bar 15 is secured a metal angle-plate 17, the attachment being made by bolts 18. The lower extremity of this plate is bent to form a horizontal part 17^a, through which the bolt 7 passes. The upper extremity of the plate 17 is provided with an angle portion 17^c, to which is attached the lower extremity of a metal strap 19. The upper extremities of each pair of straps 19 are connected above the journal-box by a bolt 20. 70 These straps 19 tie the journal-boxes down to the frame from above. The lower member 13^a of each journal-box passes between the upper extremities of a pair of side bars 15 and is secured to the said frame-bars by the 75

As shown in the drawings, the lever-bar 8 is composed of three metal plates 8^a, separated by interposed wood pieces 8^c. These parts are connected together by bolts 21. The upper 80 extremity of the lever-bar engages the eccentric 12 of the shaft 12^a, whereby an oscillating movement is imparted to the bar. Engaging the eccentric 12 of the shaft 12^a is a two-part box, each member of which is 85 designated by the numeral 4. At each side of this box is located an adjusting-plate 3, one of which is engaged by an adjusting-bolt 2, whereby as the interior box becomes worn the wear may be taken up. The lower 90 extremity of the lever-bar is provided on the side opposite the jaw 9 with a block 22, which enters the space between the metal plates 8^a, (see Fig. 2,) the filling-pieces 8^c be omitted from the lower part of the bar for this purpose. This block 22 is pivotally connected with the lever-bar by a bolt 23, and its front side bears against a pin 24, mounted on the lever. This pin is of sufficient strength to resist ordinary pressure and do ordinary work. 95 100

If, however, some article harder than the rock, as a metal part, should accidentally pass between the crushing-jaws, this pin yields or breaks to prevent injury to or the breaking 5 of the other parts. The block when the safety-pin is broken is allowed a limited degree of movement before it engages the lever, this movement being considered sufficient to allow the jaws to open to allow any ordinary obstacle to pass. The block 22 is toothed on its rear side, or that farther to the right in Figs. 1 and 2, to engage a toothed abutment 23', which is cam or eccentric shaped and adjustable to vary the space between the crushing-jaws according to the degree of fineness required in crushing the material. This segmental abutment is mounted on a large bolt 25 and is normally movable on the bolt. By loosening the tension-rod 33 the segment may 20 be turned on the bolt to adjust the lever-bar and regulate the space between the crushing-jaws as desired.

Between the crushing-jaw 9 and the metal plates 8^a of the lever-bar is a wood filling 26. 25 The lever-bar extends below its fulcrum or bearing-point on the segmental abutment, this extension being the short arm of the lever, the entire length of the lever above the fulcrum-point constituting the long arm. The 30 upper part of the jaw 9 is toothed or horizontally corrugated, as shown at 9^a, and this toothed portion is inclined rearwardly and downwardly from its upper extremity to a point A, from which it is forwardly inclined, 35 as shown at 9^b. This face 9^b of the jaw extends below the fulcrum on the lever-bar and cooperates with an oppositely-located or opposing face 27^a of the stationary jaw 27 to perform the final crushing function. The upper portion of the jaw 27 is rearwardly inclined and longitudinally corrugated, forming a wedge-shaped feed-space between the movable and stationary jaws, the said space being widest at the top and bounded at the sides by 40 cheek-plates 40.

Mounted on each side of the lever-bar and made fast thereto is a lug 30, having a vertical opening to receive a pin 31, secured to the frame on its upper extremity. The lower extremity of this pin is provided with a head, and between this head and the lug is located a coil-spring 32 to give the lever-bar a yielding support during its downward movement. The block 22 has a depending projection 22^a, 50 through which a tension-rod 33 passes. This rod also passes through one of the bottom beams 5 and is secured in place by a nut 34. Between this nut and the beam 5 is located a yielding device 35, which, as shown in the 55 drawings, is a piece of rubber. It is evident, however, that a spring or other cushion device may be employed. This tension-rod holds the toothed block 22 in operative relation with the toothed abutment.

60 The stationary jaw 27 is secured to a block

28, mounted between the beams 6 and held in place by heavy bolts 29. These bolts protrude through the beams 6 and their extremities are connected with the extremities of the bolt 25 by exteriorly-located U-shaped bars 35, one on each side of the machine. The extremities of each of these stationary bars are provided with eyes through which the extremities of the bolts 29 pass, while the bend of the bars engages the extremities of the bolt 25. By this construction the abutment and the stationary jaw or the opposing working parts of the machine are prevented from any spreading or separating action, making an exceedingly strong, durable, and efficient crushing construction 75 80 by the employment of a minimum amount of material.

From the foregoing description the use and operation of the apparatus will be readily understood. The ore or rock to be crushed is fed into the wedge-shaped space between the jaws 9 and 27. The operating-shaft 12^a is provided with a loose pulley 37 and two fly-wheels 36, one of the fly-wheels being that at the left in Fig. 3, serving as a driving-pulley 90 to be connected with a belt. (Not shown.) The eccentric-shaft being rotated the action of the eccentric moves the upper extremity of the lever-bar 8 backward, forward, and vertically. The shaft is rotated in the direction indicated by the arrow in Fig. 1. As the upper end of the bar moves toward the right (see Fig. 1) the bar is also raised. This action forces the crushing-face 9^b of the jaw 9 toward the left at the same time that the bar is lifted, thus acting on the rock both by a crushing and a grinding movement. It will be observed that while the lower extremity of the jaw 9 is moving toward the stationary jaw 27 the portion of the jaw 9 above the fulcrum-point of the abutment is moving in the opposite direction, thus opening or widening the feed-space between the jaws. On the other hand, this feed-space is closing while the face 9^b is moving away from the opposing face 27^a. Thus the rock gradually works downwardly from the feed-space into the narrow space between the crushing-faces 9^b and 27^a. It will be understood that the lever-bar acts with great force below the fulcrum-point of the abutment, since the long arm of the lever or the distance above the fulcrum is many times the length of its short arm or the distance below the abutment. 100 105 110 115

Having thus described my invention, what I claim is--

1. The combination with a suitable frame and an operating-shaft, of a lever-bar connected with the shaft, the latter being connected to impart to the bar an eccentric or crank action, a block pivotally attached to the lower extremity of the lever-bar, a breakable safety-pin, against which said block bears, and an abutment engaging the block and forming a fulcrum for the lever. 120 125 130

2. The combination with an eccentric-shaft and a suitable frame on which said shaft is journaled, of a lever-bar hung on the eccentric of the shaft, and provided with a crushing-jaw, a coöperating stationary jaw, an abutment forming a fulcrum for the lever, and yielding means giving a cushion support to the lever-bar during its downward movement, said means comprising bolts mounted on the frame and slidable in lugs fast on the lever-bar on opposite sides, and coil-springs located below the lugs and surrounding the bolts between the said lugs and the bolt-heads.
3. In a rock-crusher, the combination with a suitable frame, of a vertically-disposed lever-bar provided with a crushing-jaw, a crank-shaft connected with the upper extremity of the bar for operating the same, an abutment forming the fulcrum of the lever-bar, a bolt upon which the abutment is mounted and by which it is secured to the frame, a block pivotally mounted on the lower part of the bar, being engaged above the pivot by the abutment, and a breakable safety-pin mounted on the lever-bar.
- In testimony whereof I affix my signature in presence of two witnesses.

CHARLES WALLACE.
